ROOF ELEMENT

Willard J. Schroll, Jessup, Md., assignor to Better
Marketing Industries, Inc., Jessup, Md.

Filed Nov. 24, 1971, Ser. No. 202,067

Term of patent 14 years

Int. Cl. D25—02

U.S. Cl. D13—1 H

FIG. 1

FIG. 2

FIG. 3

FIG. 4

FIG. 5

FIG. 6

FIG. 7

FIG. 1 is a perspective view of a roof element embodying my design as seen from above one corner thereof;

FIG. 2 is a plan view of the roof element shown in FIG. 1;

FIG. 3 is a cross-sectional view of the roof element taken generally along lines 3—3 of FIG. 2;

FIG. 4 is a cross-sectional view of the roof element taken generally along lines 4—4 of FIG. 2; and

FIGS. 5, 6 and 7 are plan views similar to FIG. 2 but illustrating three modified forms of the roof design.

I claim:

The ornamental design for a roof element, substantially as shown and described.
